CLAIM

The ornamental design for a self mating beam, as shown and described.

DESCRIPTION

FIG. 1 is a top perspective view of the design of a self mating beam;

FIG. 2 is a top plan view of the self mating beam shown in FIG. 1;

FIG. 3 is a bottom plan view of the self mating beam shown in FIG. 1;

FIG. 4 is a right side view of the self mating beam shown in FIG. 1;

FIG. 5 is a left side view of the self mating beam shown in FIG. 1;

FIG. 6 is a front side view of the self mating beam shown in FIG. 1;

FIG. 7 is a back side view of the self mating beam shown in FIG. 1; and,

FIG. 8 is a top perspective view thereof, showing the self mating beam shown in FIG. 1 in an environment of use.

The broken lines in FIG. 8 illustrate environmental subject matter only and form no part of the claimed design.

The self mating beam is shown with a symbolic break in its length. The appearance of any portion of the self mating beam between the break lines forms no part of the claimed design.

1 Claim, 6 Drawing Sheets
